SAFETY CONTROL FOR GASEOUS FUEL BURNERS

Samuel G. Eskin and Charles K. Strobel, Pittsburgh, Pa., assignors to Robertshaw Thermo-stat Company, Youngwood, Pa., a corporation of Pennsylvania

Application September 24, 1941, Serial No. 412,150

9 Claims. (Cl. 158—117.1)

This invention relates to safety controls for gaseous fuel burners and, more particularly, to electrically operated controls therefor.

Gaseous fuel burners such as domestic gas ranges may have a main burner, a pilot burner ignited by an electric igniter, and means for preventing the flow of fuel to the main burner should the pilot fail to light or be extinguished after a previous lighting. It is desirable in most cases to ensure instant lighting of the pilot burner after the fuel supply thereto begins. This is particularly the case in view of the growing use of liquefied petroleum gases, such as butane and propane, in domestic gas ranges. The prolonged escape of such unburned fuel is seriously detrimental to the health of users. While a complete shut-off feature may be incorporated in such systems and is a desirable safety measure, it is apparent that serious consequences might follow upon failure of the pilot gas to ignite and bring the safety into operation. It is, therefore, an object of this invention to ensure immediate ignition of the pilot burner after the fuel supply is first turned on.

Another object of the invention is to prevent flow of fuel to the main burner whenever the pilot fails to light.

Another object of the invention is to shut off the supply of fuel to both the main and pilot burners upon physical failure of the ignition means or upon failure of the electric current supply.

Other objects and advantages will become apparent from the following description taken in connection with the accompanying drawings, wherein:

Fig. 1 is a schematic view of a control system for a gaseous fuel burner embodying this invention.

Fig. 2 is a similar schematic view of a modified form of control, and

Fig. 3 is a similar view of a further modification.

Referring more particularly to Fig. 1 of the drawings, a gaseous fuel burner 10 is supplied with fuel by a main fuel pipe 12. Such fuel supply is controlled by a main valve 14 which may be either manually or thermostatically operated. Interposed in the fuel supply pipe 12 between the main valve 14 and burner 10 is a solenoid gas valve 16 of any known type which may be arranged, as in this instance, to be opened by energization of the solenoid and closed by gravity. A pilot burner 18 is associated with the main fuel burner 10 and receives fuel from the fuel

supply pipe 12 by way of a conduit 20 connected thereto between the valve 14 and the solenoid gas valve 16. As in the case of the main fuel burner 10, the pilot burner 18 is also under the control of a solenoid gas valve 22 of similar type interposed in the conduit 20.

Electric current for the operation of the solenoid valves 16 and 22 is supplied by the line wires 24 connected to the primary of a transformer 25. The secondary of the transformer 25 is connected by a wire 26 to one terminal of a main switch which, in this instance, is incorporated in the main valve 14. Any suitable means may be used to close the switch when the main valve 14 is rotated to open position. The other terminal of the main switch is connected by a wire 28 to one terminal of the solenoid valve 22 for the pilot burner 18, the other terminal of the solenoid valve 22 being connected by a wire 30 with one end of a resistor member 32 positioned in the path of the flame from the pilot burner 18.

The resistor member 32 may be in the form of a coil of wire formed from material having normally a relatively low resistance and a positive temperature coefficient of resistance. Such elements are known as ballast resistors, but it will be apparent that other types of flame sensitive devices or thermal resistance elements having the required characteristics may be substituted. In utilizing a ballast resistor for the purpose of this invention it is necessary that the current flowing thereto does not cause it to become sufficiently heated to operate the solenoid gas valve 22 in the absence of a flame from the pilot burner 18. The selection of a suitable coil is therefore dependent upon the voltage to be used in the system as will be apparent to those skilled in the art.

The end of the ballast resistor 32 opposite that connected to wire 30 is connected by a wire 34 with one end of an electric wire incandescent igniter 36, the other end of which is connected by a wire 38 to the secondary of the transformer 25. In this embodiment an adjusting resistance element 40 is interposed in the circuit between the igniter 36 and the transformer 25 to limit the current supply to the igniter 36.

The solenoid gas valve 16 for the main fuel burner 10 is connected in series circuit with the pilot burner solenoid valve 22 and the igniter 36 and in parallel circuit with the ballast resistor 32. Such connection is made by a wire 42 which connects the wire 30 with one terminal of the solenoid gas valve 16, while the other terminal thereof is connected by a wire 44 to

a wire 46. The latter wire 46 carries a cut-out 48 and is connected at one end to the wire 34 and at the other end to one terminal of a mercury switch 50, the other terminal of which is connected by a wire 52 to the wire 28.

The mercury switch 50 is preferably of the type having a specified time delay period upon opening and an instantaneous closing. Switches of this type are disclosed in Patents Nos. 1,778,439 and 2,224,873 among others, to which reference may be had for a fuller description.

The mercury switch 50 is normally closed and is adapted to be operated to open position after a time delay period by an electromagnetic actuator 53 having one terminal connected by a wire 54 to the wire 38 and the other terminal thereof connected by a wire 56 to the wire 28. The pilot burner solenoid valve 22 is thus in series circuit with the parallel mesh of ballast coil 32, cut-out 48 and main burner solenoid valve 16 while the mercury switch 50 is connected across both the parallel mesh and the pilot burner solenoid valve 22. The electromagnetic actuator 53 for the mercury switch 50 is connected as described across the secondary of the transformer 25 through the main switch incorporated in the valve 14.

In the operation of the safety control apparatus shown in Fig. 1 the closing of the main switch of valve 14 is effected upon opening of this valve as described and permits fuel to flow in the main fuel pipe 12 and the conduit 20 as far as the main burner solenoid valve 16 and the pilot burner solenoid valve 22, respectively. The electric current flows through the wire 26 from the secondary of the transformer 25 through the main switch of valve 14 and through the wires 28 and 52 to the mercury switch 50. This switch being closed at this time, the current flows therefrom through the wire 46 and wire 34 to the ignition coil 36. The wire 38 which is connected to the other end of the ignition coil 36 conveys the current through the adjusting resistor 40 back to the secondary of the transformer 25. During this time, the current is also flowing through the wires 56 and 54 to the electromagnetic actuator 53 of the mercury switch.

After a definite time delay, which in this instance may be eighteen seconds, the mercury switch 50 opens. During the time delay period the ignition coil has reached igniting temperature and the unburned gases which ordinarily surround it have had time to flow away. The opening of the mercury switch causes current to flow through the wire 28 to the pilot burner solenoid valve 22 and then by way of wire 30 and wire 42 to the main burner solenoid valve 16. The wire 44 which is connected to the other terminal of the main burner solenoid valve 16 conveys the current to wire 46 which is connected to the wire 34 of the ignition coil circuit. At the same time the ballast resistor 32 which is shunted across the main burner solenoid valve 16 is also introduced into the circuit.

Energization of the pilot burner solenoid valve 22 by the means described causes it to open and permit fuel to flow through the conduit 20 to the pilot burner 18 where it is ignited by the ignition coil 36. The flame of the pilot burner heats the ballast coil 32 and its temperature increases with corresponding increase in its resistance until sufficient electric current is caused to flow through the main burner solenoid valve 16 to open this valve. Consequently, the fuel then permitted to flow through the main fuel pipe 12

to the main burner 10 becomes lighted by the flame from the pilot burner 18 and the ignition sequence is completed.

From the sequence of operations described it will be apparent that the pilot burner fuel supply is not permitted to flow thereto until a definite period after the ignition coil has been energized. The flow of fuel to the main burner is not permitted until after the pilot flame is burning and the ballast coil becomes heated thereby. It will furthermore be apparent that if the ignition coil burns out or becomes open circuited the gas supplies to both the main and pilot burners are shut off. If the ballast coil becomes open circuited the cut-out in series with the main burner solenoid valve causes this valve to close.

It is of importance that the turning on, then off and then on again of the main switch does not cause escape of unburned fuel due to opening of the main burner solenoid valve before the ignition coil has reached igniting temperature as may occur in other forms of control. The main burner solenoid valve of this invention remains closed until the time delay period has expired regardless of the speed of recycling the control. The instantaneous reset feature of the circuit for on-off-on cycles is thus of great advantage.

The embodiment of the invention shown in Fig. 2 of the drawings has the described features with provision for preventing current flow through the main burner solenoid in the event that the pilot burner solenoid becomes short circuited. In this embodiment a main fuel burner 60 is supplied with fuel by a main fuel pipe 62 controlled by a main valve 64 and having a main burner solenoid gas valve 66 interposed therein. A pilot burner 68 is associated with the main fuel burner 60 and receives fuel from the fuel supply pipe 62 by way of a conduit 70 connected thereto between the valve 64 and the main burner solenoid gas valve 66. In this embodiment the pilot burner solenoid gas valve 72 which is interposed in the pilot burner conduit 70 is of a special type having a front contact 74 which is adapted to be operated between open and closed positions by normal movement of the solenoid armature included in such types of valve.

Electric current for the operation of the valves 66 and 72 is supplied by the line wires 76 connected to the primary of a transformer 78. The secondary of the transformer 78 is connected by a wire 80 to one terminal of a main switch which, as in the previous instance, is incorporated in the main valve 64. Any suitable means known to those skilled in the art may be used to close the switch when the main valve 64 is rotated to open position. The other terminal of the main switch is connected by wires 82 and 108 to one terminal of the solenoid valve 72 for the pilot burner 68, the other terminal of the solenoid valve 72 being connected by wires 84 and 112 with one end of the ignition coil 86. The other end of the ignition coil 86 is connected by a wire 88 to the secondary of the transformer 78, there being an adjusting resistance element 90 interposed in the circuit between the igniter 86 and the transformer 78 to limit the current supply to the igniter 86.

In this embodiment the main burner solenoid valve 66 is in parallel circuit with the igniter 86 and the pilot solenoid valve 72. Such connection is made by a wire 92 extending from the wire 82 to one terminal of the front contact 74 of the solenoid valve 72. The other terminal

of the front contact 74 is connected by a wire 94 to one end of a ballast resistor 96 similar to that described in connection with the previous embodiment. The other end of the ballast resistor 96 is connected by a wire 98, having a cut-out 100 incorporated therein, to one terminal of the solenoid gas valve 66. The other terminal of the main burner solenoid gas valve 66 is connected by a wire 102 with the wire 94. The ballast resistor 96 is thus in parallel circuit with the main burner solenoid valve 66.

The mercury switch 104 of this embodiment has one terminal connected by a wire 106 to the wire 82 at the junction of the wire 108 therewith. The switch 104 is thus connected to one terminal of the solenoid valve 72. The other terminal of the mercury switch 104 is connected by a wire 110 to the wire 84 at the junction of the wire 112 therewith. The connection of the switch 104 to the other terminal of the pilot burner solenoid valve 72 is thus completed. The electromagnetic actuator 114 for the mercury switch 104 has one terminal connected by a wire 116 to the wire 82 at the junction of the wire 92 therewith, while the other terminal thereof is connected by a wire 118 to the wire 88.

Connected in series circuit with the parallel mesh of the main burner solenoid valve 66 and ballast resistor 96 is a series resistor 120 having a wire 122 connecting one end thereof with the wire 88 and a wire 124 connecting the opposite end thereof with the wire 88 at the junction of the wire 118 therewith.

The operation of the device shown in the embodiment of Fig. 2 is commenced by closing of the main switch of valve 64 which opens the valve and permits fuel to flow in the main fuel pipe 62 and the conduit 70 as far as the main burner solenoid valve 66 and the pilot burner solenoid valve 72, respectively. The electric current flows through the wire 80 from the secondary of the transformer 78 through the main switch of valve 64 and through the wires 82 and 106 to the mercury switch 104. This switch being closed at this time, the current flows therewith through the wire 110 and wire 84 to the ignition coil 86. The wire 88 which is connected to the other end of the ignition coil 86 conveys current through the adjusting resistor 90 back to the secondary of the transformer 78. The current at this time also flows through the wires 116 and 118 to the electromagnetic actuator 114 of the mercury switch.

After a definite time delay, which in this instance may be eighteen seconds, the mercury switch 104 opens. During this period the ignition coil has reached igniting temperature and the unburned gases which ordinarily surround it have had time to flow away. The opening of the mercury switch causes current to flow through the wire 108 to the pilot burner solenoid valve 72 and then by way of wire 112 through the ignition coil circuit. The pilot burner solenoid valve 72 being thus energized, it is moved to open position and the flow of fuel from the pilot burner 68 is ignited by the igniter 86.

When the pilot solenoid valve 72 opens, the front contact 74 thereof is automatically closed by movement of the solenoid armature. Such closing of the front contact 74 causes current to flow by way of the wires 94 and 102 to the main burner solenoid valve 66. However, at this time sufficient current does not flow through the main burner solenoid valve 66 to move it to open position. When the pilot flame heats the

ballast resistor 96 sufficiently its resistance increases and causes sufficient current to flow through the solenoid of the main burner solenoid gas valve 66 to open it and permit fuel to flow to the main burner 68. The fuel flowing from the main burner 68 is then ignited by the flame from the pilot burner 68.

As will be apparent, the embodiment shown in Fig. 2 has all the desirable features of the embodiment shown in Fig. 1. Moreover, in the embodiment shown in Fig. 2 short circuiting of the pilot solenoid will cause the front contact 74 thereon to remain open so that no current can flow through the main burner solenoid valve 66 to cause operation thereof.

An alternate form of the modification shown in Fig. 2, but substituting a double-time delay mercury switch for the front contact type of pilot solenoid valve, is shown in Fig. 3. In this embodiment a main fuel burner 130 is supplied with fuel by a main fuel pipe 132 controlled by a main valve 134 and having a main burner solenoid gas valve 136 interposed therein. A pilot burner 138 is associated with the main fuel burner 130 and receives fuel from the fuel supply pipe 132 by way of a conduit 140 connected thereto between the main valve 134 and the main burner solenoid gas valve 136. In this embodiment the pilot burner solenoid gas valve 142 which is interposed in the pilot burner conduit 140 may be similar to that described in connection with the embodiment of Fig. 1.

Electric current for the operation of the solenoid valves 136 and 142 is supplied by the line wires 144 connected to the primary of a transformer 146. The secondary of the transformer 146 is connected by a wire 148 to one terminal of a main switch which, as in the previous instances, is incorporated in the main valve 134 and any suitable means known by those skilled in the art may be used to close the switch when the main valve 134 is rotated to open position. The other terminal of the main switch is connected by wires 150 and 152 to one terminal of the solenoid valve 142 for the pilot burner 138, the other terminal of the solenoid valve 142 being connected by wires 154 and 156 with one end of the ignition coil 158. The other end of the ignition coil 158 is connected by a wire 160 to the secondary of the transformer 146, there being an adjusting resistance element 162 interposed in the circuit between the igniter 158 and the transformer 146 to limit the current supply to the igniter 158.

As in the embodiment of Fig. 2 the main burner solenoid valve 136 is connected in a second circuit which is in parallel circuit with that of the pilot solenoid valve 142. However, also as in the previous embodiment, a ballast coil 164 forms part of the main burner solenoid circuit and is connected in parallel circuit with the main burner solenoid valve 136. The connections of the ballast coil 164 to the main burner solenoid valve 136 are made by the wires 166 and 168, there being a cut-out 170 incorporated in the wire 166 between the main burner solenoid valve 136 and the ballast coil 164. Connected in series circuit with the parallel mesh of the main burner solenoid valve 136 and the ballast resistor 164 is a series resistor 172 having a wire 174 connecting one end thereof with the wire 166 and a wire 176 connecting the opposite end thereof with the wire 160.

The double-time delay mercury switch previously mentioned may comprise a pilot solenoid

valve switch 178 and a main burner solenoid valve switch 180. Both switches are normally closed and may be actuated to open position by a single solenoid 182 having one terminal connected by a wire 184 with the wire 160 and the other terminal connected by a wire 186 with the wire 160. The mercury switch 178 for the pilot burner solenoid valve 142 is connected in shunt therewith by the wires 188 and 190, the wire 188 being connected to the wire 160 and the wire 190 being connected to the wire 164. The mercury switch 180 for the main burner solenoid valve 136 is connected in shunt with the parallel mesh of this valve 136, the ballast coil 164 and the cut-out 170. Such connection is made by a wire 192 connecting one terminal of the switch 180 with the wire 168 and by a wire 194 connecting the other terminal of the switch 180 with the wire 166 between the cut-out 170 and ballast coil 164. The circuit of the series resistor 172 in series with the parallel mesh of ballast coil 164 and main burner solenoid valve 136 is completed by a wire 198 connected at one end to the wire 162 and at the other end to the wire 192 extending from the mercury switch 180.

Preferably, the mercury switch 180 which shunts the main burner solenoid valve 136 has a longer time delay period than the mercury switch 178 which shunts the pilot burner solenoid valve 142. After the ignition coil has reached igniting temperature the delay period for opening of the mercury switch 178 expires and permits the pilot burner solenoid valve 142 to become energized and moved to open position. Fuel then flows from the pilot burner 138 and is ignited by the igniter 158. After a further delay period, the mercury switch 180 opens and causes current to flow to the main burner solenoid valve 136. Meanwhile, the pilot flame has heated the ballast resistor 164 during the delay period to increase its resistance and permit sufficient current to flow through the main burner solenoid to energize it and open the valve. The fuel then flows from the main burner 130 to become ignited by the pilot burner flame and the cycle is complete.

We claim:

1. In an electrical ignition system for fuel burners having main and pilot burners and means for supplying fuel thereto, an electric igniter for the pilot burner, separate electrically operable means energizable for actuation to a position for admitting fuel to the main and pilot burners when current of sufficient value is supplied to said fuel admitting means, an energizing circuit including said igniter and fuel admitting means, control means electrically connected to said fuel admitting means for preventing the same from receiving current of said value for a predetermined period following energization of said igniter, said control means including an initially closed switch which opens after a time-delay period following energization of said control means and resets for such delay period substantially instantaneously upon deenergization of said control means, and a thermal resistance element electrically connected to said main burner fuel admitting means and located to be heated by a flame at the pilot burner, said element being adapted to prevent said main burner fuel admitting means from receiving current of said value for actuation thereof until said element is heated by said flame.

2. In an electrical ignition system for fuel burners having main and pilot burners and means for supplying fuel thereto, an electric

igniter for the pilot burner, separate electrically operable means energizable for actuation to a position for admitting fuel to the main and pilot burners when current of sufficient value is supplied to said fuel admitting means, an energizing circuit including said igniter and fuel admitting means, control means for preventing said pilot burner fuel admitting means from receiving current of said value for a predetermined period following energization of said igniter, said control means including an initially closed switch in shunt with said pilot burner fuel admitting means and being adapted to open after a time-delay period following energization of said control means and to reset for such delay period substantially instantaneously upon deenergization of said control means, and a thermal resistance element in shunt with said main burner fuel admitting means and located to be heated by a flame at the pilot burner, said element having insufficient resistance value until heated by said flame for current of said sufficient value to be supplied to said main burner fuel admitting means.

3. A safety control apparatus for gaseous fuel burners having main and pilot burners and means for controlling the supply of fuel thereto, said apparatus comprising an electric igniter for said pilot burner energized by operation of said controlling means, a normally closed solenoid valve in series circuit with said igniter for preventing the supply of fuel from passing to the pilot burner from said controlling means, and a control relay for shunting said valve, said relay comprising a mercury switch occupying a closed position when said circuit is deenergized and having time-delayed movement to open position permitting the igniter to reach igniting temperature before the solenoid valve opens.

4. A safety control apparatus for gaseous fuel burners having main and pilot burners and means for controlling the supply of fuel thereto, said apparatus comprising an electric igniter for said pilot burner energized by operation of said controlling means, a normally closed solenoid valve in series circuit with said igniter and intercepting the fuel supply to the pilot burner, a control relay having a timing element connected in parallel circuit with said solenoid valve and operable to delay actuation thereof to open position until the igniter reaches igniting temperature, a normally closed solenoid valve electrically connected with said igniter and pilot burner solenoid valve for preventing the supply of fuel from passing to the main burner from said controlling means, and a thermal resistance element electrically connected to the main burner solenoid valve and exposed to a flame upon operation of the pilot burner for governing the operation of said last named valve.

5. A safety control apparatus for gaseous fuel burners having main and pilot burners and means for controlling the supply of fuel thereto, said apparatus comprising an electric igniter for said pilot burner energized by operation of said controlling means, a normally closed solenoid valve in series circuit with said igniter and intercepting the fuel supply to the pilot burner, a control relay having a timing element connected in parallel circuit with said solenoid valve and operable to delay actuation thereof to open position until the igniter reaches igniting temperature, a normally closed solenoid valve electrically connected with said igniter and pilot burner solenoid valve for preventing the supply of fuel from passing to the main burner from said controlling means, and a

thermal resistance element having normally a relatively low resistance and a positive temperature coefficient of resistance electrically connected in parallel circuit with said main burner solenoid valve and exposed to the flame of the pilot burner for governing the operation of said last named valve.

6. A safety control apparatus for gaseous fuel burners having main and pilot burners and means for controlling the supply of fuel thereto, said apparatus comprising an electric igniter for said pilot burner energized by operation of said controlling means, a normally closed solenoid valve in series circuit with said igniter and intercepting the fuel supply to the pilot burner, a control relay having a timing element connected in parallel circuit with said solenoid valve and operable to delay actuation thereof to open position until the igniter reaches igniting temperature, a normally closed solenoid valve electrically connected with said igniter and pilot burner solenoid valve for preventing the supply of fuel from passing to the main burner from said controlling means, means operable by said pilot burner for governing the operation of said main burner solenoid valve to open position, and means responsive to actuation of the pilot burner solenoid valve for opening and closing the circuit of said main burner solenoid valve.

7. A safety control apparatus for gaseous fuel burners having main and pilot burners and means for controlling the supply of fuel thereto, said apparatus comprising an electric igniter for said pilot burner energized by operation of said controlling means, a normally closed solenoid valve in series circuit with said igniter and intercepting the fuel supply to the pilot burner, a control relay having a timing element connected in parallel circuit with said solenoid valve and operable to delay actuation thereof to open position until the igniter reaches igniting temperature, a normally closed main burner solenoid valve connected in parallel circuit with said igniter and pilot burner solenoid valve for preventing the supply of fuel from passing to the main burner from said controlling means, a thermal resistance element connected in parallel circuit with said main burner solenoid valve and exposed to a flame upon operation of the pilot burner for governing the operation of said last named valve, and a switch connected in series circuit with said main burner solenoid valve and responsive to actuation of the pilot burner sole-

noid valve for opening and closing the circuit of said main burner solenoid valve.

8. A safety control apparatus for fuel burners having a main burner, a pilot burner, means for supplying fuel to said burners, an electric igniter for said pilot burner, separate electrically operable means energizable for actuation from closed to open position for admitting the supply of fuel to the main and pilot burners, an energizing circuit for said igniter and fuel admitting means, a control relay having a timing element in shunt with the pilot burner fuel admitting means, said shunt being established upon energization of said circuit and removable by operation of said relay after a time-delay period during which said fuel admitting means remain closed and said igniter reaches igniting temperature, and a thermal resistance element adapted to be exposed to the flame of said pilot burner and having normally a relatively low resistance and a positive temperature coefficient of resistance connected in shunt with said main burner fuel admitting means, said last named shunt being adapted to prevent actuation of said main burner fuel admitting means until said element is heated by the flame of the pilot burner.

9. A control system for fuel burners having main and pilot burners and means for supplying fuel thereto comprising in combination, a source of electrical energy, electrically operated means connected to said source for controlling the supply of fuel to the main burner, said controlling means having an initial closed position preventing fuel supply to the main burner and being actuatable to an open position when current of sufficient value is supplied to said controlling means, a thermal resistance element shunting said controlling means and being located to be heated by a flame at the pilot burner, said resistance element having insufficient resistance value until heated by said flame for current of said sufficient value to be supplied to said controlling means, and switching means having a timing element for short-circuiting said controlling means for the period during which said resistance element is becoming heated, whereby current of said sufficient value for causing actuation of said controlling means is supplied thereto upon operation of said switching means to discontinue the said short circuit.
